UNITED STATES PATENT OFFICE.

GEORGE GODDU, OF WINCHESTER, MASSACHUSETTS, ASSIGNOR TO UNITED SHOE MACHINERY COMPANY, OF PATERSON, NEW JERSEY, A CORPORATION OF NEW JERSEY.

MACHINE FOR INSERTING FASTENINGS.

1,124,417.

Specification of Letters Patent. Patented Jan. 12, 1915.

Original application filed February 8, 1909, Serial No. 476 649. Divided and this application filed April 17, 1912. Serial No. 691,435.

To all whom it may concern:

Be it known that I, GEORGE GODDU, a citizen of the United States, residing at Winchester, in the county of Middlesex and 5 State of Massachusetts, have invented certain Improvements in Machines for Inserting Fastenings, of which the following description, in connection with the accompanying drawings, is a specification, like 10 reference characters on the drawings indicating like parts in the several figures.

This invention relates to machines for inserting previously formed fastenings, such, for example, as headed nails or tacks, and 15 particularly to fastening feeding mechanisms for use in such machines.

Fastening inserting machines which are used to insert headed fastenings are usually provided with raceways down which the fastenings are conducted from the hopper or 20 other source of supply into position to be operated upon by the separator or other fastening delivering mechanism. These raceways are usually long enough to hold a considerable number of fastenings, especially 25 when the machine is to be operated at high speed, since it is important that there be no interruption in the delivery of fastenings to the inserting mechanism such as might occur if the fastenings should become temporarily clogged at the upper end of a short 30 raceway. When it is desired to change from one length of fastening to another in a machine provided with a comparatively 35 long raceway, difficulty is sometimes experienced in removing the fastenings quickly from the raceway. This operation usually takes considerable time and is frequently most quickly accomplished by re- 40 moving the raceway from the machine and shaking the nails or other fastenings out of one end of it.

An object of the present invention is to provide an improved raceway from which 45 the fastenings may be quickly removed when it is desired to change from one length of fastening to another, or when it is desired to remove the fastenings for any other purpose. In its illustrated embodiment this ob- 50 ject of the invention is attained by making provision, preferably at a point between the ends of the raceway, for quickly and easily enlarging the fastening guiding groove in

the raceway so that the fastenings may drop through the bottom of the raceway.

55

In the accompanying drawings which illustrate a preferred embodiment of the invention,—Figure 1 is a perspective view of a raceway having provision, in accordance with the invention, for quickly removing the fastenings therefrom, the raceway being shown as broken away at the upper end; Fig. 2 is a sectional view of the raceway illustrating in detail the mode of operation of the improvements which constitute the 65 invention.

The raceway 2 down which the fastenings slide from a fastening container 3 is provided with a groove 4, this groove being narrow at the top so that the head of the nail 70 or tack may rest upon the sides 6 and 8 of the groove while the shank depends in the groove. Below the narrow portion the groove is enlarged at 10, this enlarged portion of the groove being wide enough to 75 permit the nails to fall through it in the event that they come into it. The raceway is preferably composed of two separate plates fastened together by bolts 12.

In order that the nails may fall clear of 80 the fastening inserting machine and also in order that it may not interfere with the proper construction of the lower end of the raceway, the provision for removing the 85 nails is made just above the lower end of the raceway, as shown in Fig. 1. In the illustrated construction the side 8 of the groove in the raceway is provided near the lower 90 end of the raceway with a slot 14 into which fits the upper end of a lever 16 pivoted at 18 between ears 20 formed upon the side 8, the side 8 being the side nearer the operator when the raceway is located in the machine. The upper end of the lever 16 is so shaped that when it is in position in the slot 14 it 95 makes the side of the raceway in which the slot is formed continuous. To insure its proper location in the slot the lever is so shaped that when it has been turned about its pivot 18 until the face or shoulder 22 100 strikes the bottom of the slot 14 the continuity of the raceway will be complete.

The lever 16 is preferably held normally in the position in which it completes the raceway and any suitable means may be 105 provided for this purpose, such, for ex-

ample, as a set screw 24 in the lower end of the lever bearing against the side of the raceway. When it is desired to remove the nails from the raceway, the operator turns the set screw 24 to release the lever 16 and then moves the lever into the dotted line position shown in Fig. 2, thus enlarging the groove 4 so that the heads of the nails will drop through into the groove 10. The nails at the lower end of the raceway may be removed by sliding them back until they come over the enlargement in the groove 4 or they may be removed one at a time by operating the machine.

15 The foregoing arrangement for emptying the raceway may conveniently be designated as a "trap."

The raceway herein shown and described may obviously be used with a number of different types of fastening inserting machines. An example of a machine with which it is especially useful is the fastening inserting machine of my co-pending application, Ser. No. 476,649, filed Feb. 8, 1909, 25 of which application the present application is a division.

Having described my invention, what I claim as new and desire to secure by Letters Patent of the United States is:—

30 1. In a machine of the class described, a fastening container and a normally continuous inclined raceway down which the fastenings from said container, while supported by said raceway, may gravitate into position to be operated upon, said raceway having between said container and the delivery end of said raceway means for quickly effecting, at the will of the operator and under the action of gravity, a discharge 35 of the portion of the raceway above said means.

2. In a machine for inserting fastenings, a fastening container and a normally continuous inclined raceway arranged to conduct the fastenings from the container to the point at which the fastening inserting operation takes place, said raceway having between said container and its delivery end means for discharging fastenings through 40 the bottom thereof when it is desired to empty the raceway.

3. In a machine for inserting fastenings,

a fastening container, and an inclined raceway having a fastening guiding groove dimensioned to support the head of the fastening upon its sides while the shank depends in said groove, said raceway being arranged to conduct the fastenings from said container to the point at which the fastening inserting operation takes place and having means at a point between said container and its delivery end for enlarging said groove to such dimensions that it will not support and guide the fastenings whereby the fastenings above said point will gravitate out of the raceway.

4. In a machine of the class described, a fastening container, an inclined raceway arranged to conduct the fastenings from said container to the point at which they are to be operated upon, said raceway having a fastening guiding groove which is provided with a wall having a movable section at a point near the delivery end of said raceway, and means for positioning and normally maintaining said section so that it cooperates with the opposite wall to sustain and guide the fastenings, said means being constructed to permit said section to be moved away from the other wall whereby the fastenings may be removed from the raceway through the bottom thereof without exposing the delivery end of said raceway.

5. In a machine of the class described, a fastening container and an inclined raceway arranged to conduct the fastenings from said container to the point at which they are to be operated upon, said raceway having a fastening guiding groove smaller at the top than at the bottom and having means at a point between said container and the delivery end of said raceway for enlarging said groove at the top to permit the fastenings to be removed from the bottom when it is desired to empty said raceway without operating upon the fastenings.

In testimony whereof I have signed my name to this specification in the presence of two subscribing witnesses.

GEORGE GODDU.
